WINDOW SHADE PULL

George B. C. Miller, Jr., Baltimore, Md.

Application August 14, 1951, Serial No. 241,791

3 Claims. (Cl. 160—384)

1
This invention relates to a window shade pull adapted for attachment to the shade stick hem of a conventionally formed fabric or paper window shade.

An important object of the present invention is to provide a window shade pull so formed as to protect the shade from being torn by the fingernails of one raising or lowering the shade or by a pull device extending angularly from the shade.

A further important object is to provide a shade pull that will be capable of being manufactured at very low cost, from material which would ordinarily be discarded by the manufacturer as waste.

Yet another object is to provide a pull of the type stated so designed as to permit its application to window shades already in use, the pull being adapted for application to the shade with considerable speed and facility.

Yet another object is to provide a pull as described which may comprise a tab of flexible material adapted to be folded medially upon itself to define a pair of side walls connected at one end thereof, with said side walls having lower portions disposed in face to face contact below and in the plane of the shade to provide a convenient tab member whereby the shade may be gripped to raise and lower the same, said side walls further having upper side wall portions diverging from the lower portions in embracing relationship to the shade stick hem and adapted to be conformed, by reason of the flexible nature thereof, to the cross sectional configuration of the particular shade stick hem to which the device is applied.

Still another object is to provide a tab support for use with the tab referred to above, that will be also formed of flexible material so as to be capable of being conformed to the cross sectional configuration of the shade stick hem, and which will be adapted to reinforce the hem in the vicinity of the pull tab.

Other objects will appear from the following description, the claims appended thereto, and from the annexed drawing, in which like reference characters designate like parts throughout the several views, and wherein:

Figure 1 is a side elevational view of a pull tab and its associated tab support, as they appear when applied to the shade stick hem of a conventional window shade, said shade and hem being illustrated fragmentarily and in side elevation;

Figure 2 is a sectional view taken on line 2—2 of Figure 1;

Figure 3 is a plan view of the blank from which the tab support is formed, in which one corner is turned up to show the opposite face of the blank;

2
Figure 4 is a plan view of the blank from which the tab is formed, spaced corners of said tab blank being turned upwardly to illustrate the opposite face of the blank;

5
Figure 5 is a view similar to Figure 1, showing a modified means of attaching the tab support and tab to the shade; and

10
Figure 6 is a view similar to Figure 1 showing another modified means for attaching the tab support and tab to the shade;

Referring to the drawing in detail, a thoroughly conventional window shade has been illustrated fragmentarily in the drawings, and is generally designated 10. Along its bottom edge 15 the shade is formed with a shade stick hem 12, said hem being formed by folding the lower edge portion of the shade upon itself, and securing the folded portion by means of a longitudinal series of stitches 14.

20
Positioned within the shade stick hem is a shade stick 16, which may be of any cross sectional configuration and which, as will be understood, conforms the opposite sides of the hem to a cross sectional shape corresponding to the cross sectional shape of the opposite sides of said stick.

The invention includes a tab support generally designated 18, said tab support being generally rectangular when viewed in blank, as may be readily noted from Figure 3, and being preferably provided with rounded corners. The tab support, in this connection, is formed of flexible material throughout, and can in fact be formed of the same material as that used in the manufacture of the shade. As a result, the manufacturer is enabled to form the tab support from scraps or remnants of shade material that might otherwise be discarded.

40
In the form of the invention illustrated in Figures 1 to 4 inclusive, the tab support, on one face thereof, is provided with adhesive material 20. Accordingly, the tab support may be folded upon itself medially between opposite ends thereof, so as to extend around the shade stick and the shade stick hem in embracing relation thereto. By reason of the flexible nature of the material from which the tab support is formed, the support is conformed to the cross sectional configuration of the shade stick hem, as may be readily noted from Figure 2.

After having been positioned relative to the hem, as illustrated in Figures 1 and 2, the tab support is adhesively secured to the hem.

A pull tab has been generally designated 22, and is also generally rectangular in blank, the pull tab being formed with rounded corners;

Intermediate opposite ends of the pull tab, said tab is formed with opposed notches 24, aligned transversely of the pull tab blank, and respectively having rounded or curving side walls.

Extending between the apices of the notches is a score line 26, along which the blank may be folded upon itself.

When the blank is folded upon itself, it appears as illustrated in Figures 1 and 2, and the folding of the blank defines a pair of side walls equal in length and width, the respective edges of which register with one another.

Each side wall is formed with a lower side wall portion 30, the respective wall portions 30 being disposed in face to face contact with one another as seen from Figure 2, and being adhesively secured in this relationship through the provision of adhesive material 28 provided upon one face of the pull tab blank. The contacting lower wall portions are disposed in the plane of and below the shade 10, so as to provide a convenient grip for one desiring to raise and lower the shade. Obviously, when the tab is gripped, there will be no pull exerted upon the shade 20 obliquely to the plane thereof, which obliquely or angularly exerted pull might tend to tear the fabric of which the shade is formed. Further, the gripping of the depending tab portion defined by the wall portions 30 eliminates the possibility of the fabric of the shade being torn or soiled as it otherwise might be if gripped directly by the hand of the user.

The lower side wall portions 30 merge into upper side wall portions 32, that diverge upwardly from the lower side wall portions (Figure 2), into embracing relationship to the opposite sides of the shade stick hem. By reason of the flexible nature of the upper side portions 32, said portions are conformed to the cross sectional configuration of the hem, and are adhesively secured to the opposite sides of the hem through the medium of the adhesive material 28.

I believe that it will be apparent that the particular formation of the tab support and the tab is such as to permit them to be applied to a shade stick hem of any cross sectional configuration, without necessity of changing the design or material or dimensions of said support and tab.

Referring to Figure 5, a tab support 18 and pull tab 22 are formed identically to those illustrated in Figures 1-4. However, in this instance the adhesive material 20, 28 is not used. Instead, the tab support is secured to the material of the hem 12 by means of a marginal row of stitches 34. Thereafter, the pull tab is secured to the tab support through the provision of a marginal series of stitches 34, extending peripherally of the upper side wall portions 32.

In Figure 6, a second modified means of attaching the support and pull tab to the shade is illustrated. In this instance, the tab support is secured to the hem by means of staples 36, and the tab is secured to the tab support and hem by a single staple 36. Obviously, the staples 36 can extend not only through the fabric from which the hem is formed, but directly into the shade stick, thus to provide a rigid, strong connection of the device to the window shade.

It is believed clear that the invention is not necessarily confined to the specific use or uses thereof described above, since it may be utilized for any purpose to which it may be suited. Nor is the invention to be limited to the specific construction illustrated and described, since such construction is only intended to be illustrative of the principles of operation and the means pres-

ently devised to carry out said principles, it being considered that the invention comprehends any minor changes in construction that may be permitted within the scope of the appended claims.

What is claimed is:

1. A window shade pull including a tab of flexible material folded medially upon itself to define a pair of side walls of equal length interconnected at one end thereof, said side walls having lower side wall portions contiguous to the connected ends of the side walls and joined in face to face contact for disposition in the plane of a window shade below the shade stick hem thereof, said lower portions merging into upper side wall portions, said upper portions diverging upwardly from the lower portions in embracing relationship to said hem and adapted by the flexible nature thereof to be conformed to the cross sectional configuration of the respective sides of the hem.

2. A window shade pull including a tab generally rectangular in blank and formed of flexible material throughout, said tab being transversely folded upon itself medially between its ends to define a pair of side walls equal in length and equal in width and integrally interconnected at one end thereof, said side walls being formed integrally with lower side wall portions contiguous to the connected ends thereof, said lower portions being joined in face to face contact for disposition in the plane of a window shade below the shade stick hem thereof, said lower portions merging into upper side wall portions which diverge upwardly from the lower portions in embracing relationship to said hem and adapted by the flexible nature thereof to be conformed to the cross sectional configuration of the respective sides of the hem.

3. A window shade pull including a generally rectangular tab support of material flexible throughout conformed to the cross sectional configuration of and embracing the shade stick hem of a window shade; and a tab of material flexible throughout and generally rectangular when viewed in blank, said tab being transversely folded upon itself medially between its ends to define a pair of side walls equal in length and equal in width, integrally interconnected at one end thereof, said side walls being integrally formed with lower side wall portions, contiguous to the connected ends thereof, said lower portions being joined in face to face contact for disposition in the plane of a window shade below the shade stick hem thereof, said lower portions merging into upper side wall portions and diverging upwardly from the lower portions in embracing relationship to said tab support and adapted by the flexible nature thereof to be conformed to the cross sectional configuration of the tab support and of the respective sides of the hem, said tab having its upper portions secured to the tab support, for supporting of the tab by said support.
